UNITED STATES PATENT OFFICE.

JAMES J. SULLIVAN, OF TOLEDO, OHIO.

ARTICLE OF FURNITURE.

Application filed November 14, 1925. Serial No. 68,937.

This invention relates to articles of furniture, but particularly relates to that type of couches or davenport having an extensible supporting surface.

5 Objects of this invention are to provide an article of furniture having an extensible supporting surface composed of movable spring elements which may be extended into position of use to one side of the frame, or 10 may be compacted together when not in use into a relatively small space; and to provide an article of furniture having the new and improved features of construction and arrangement hereinafter described.

15 The invention is shown by way of illustration in the accompanying drawings, in which:

Fig. 1 is a horizontal sectional view of a davenport embodying my invention showing the extensible support in folded or compacted position; Fig. 2 is a view similar to Fig. 1, but showing the parts extended in position of use; and Fig. 3 is a fragmentary elevation of a corner of the davenport 25 showing the manner of stretching the spring elements into useful supporting position.

The illustrated embodiment of the invention comprises a davenport having a stationary main frame 1 which may be provided with the usual box cushion structure 2^a to receive the seat cushions 2. The front 30 of the frame is closed by a panel 3 and this panel may be suitably upholstered, stained or finished in any suitable or desired manner, as is usual with furniture of this type.

35 Formed on the opposite ends of the frame 1 are channeled guides 4 and 5 respectively, and the guide 5 is inclined outwardly toward one end of the frame. Slidably in the 40 guides 4 and 5 are arms 6 and 7 respectively, having rollers 8 engageable in the guides. The outer ends of the arms 6 and 7 are connected to the inner side of the front panel 3 and the arm 6 is fixed to the 45 panel 3.

The arm 7 is connected to a link 9 having a pair of longitudinally elongate slots 10 and 11, spaced from each other, and a guide pin 12 on the panel 3 projects into the slot 50 11. A handle 13 is pivoted to the panel 3 by a pin 14 extending through the slot 11, and the handle 13 is connected by a link 15 to the link 9. It will thus be seen that when the handle 13 is moved to the right, the arm 55 7 will also be moved to the right and movement of the handle 13 to the left will also

move the arm 7 to the left to the position shown in full lines on Fig. 2.

It will readily be seen that when the arms 6 and 7 are moved inwardly in the frame 1 by means of the panel 3, the arm 6 will move in approximately a straight horizontal line, but the arm 7 will be inclined inwardly because of the inclination of the 60 guide track 5.

65 Slidably connected to the arms 6 and 7 at the opposite ends are a series of spring elements 15 and each element comprises a pair of helical springs 16 which are connected together by means of a link or wire 70 17. The several spring elements are connected together by means of chains or links 18, or in any other suitable manner, and the spring element adjacent the front panel 3 is also connected thereto by means of links 75 or chains.

Normally, the several spring elements 17 are positioned in compact relation in close juxtaposition to each other at the forward portion of the davenport, and for this purpose the spring cushion structure 2^a may be formed with a recess in which the spring elements 17 may be positioned when not in use, and by positioning these elements in the forward portion of the davenport frame, the 80 cushioning action of the cushion structure 2^a is not interfered with.

85 When it is desired to increase the supporting surface of the davenport in order to convert the couch into a bed, the panel 3 may be 90 grasped and pulled outwardly, and in doing this the several spring elements 15 will be separated relatively to each other owing to the interconnecting chains or links 18, so as to assume the position indicated in Fig. 2. 95 When fully extended, the arm 7 will assume the position indicated by the dotted lines in Fig. 2, in which position the several spring elements 15 will be loose.

In order to make the spring elements 15 100 taut, the handle 13 is swung to the left, thereby forcing the arm 7 outwardly to bring the spring elements into useful supporting position. In order to return the panel 3 to its former position, the handle 105 13 is swung to the right in which position the spring elements will not be taut, although it is preferable that they maintain sufficient tautness so that but little or no sagging takes place. It is to be understood, 110 however, that when in compacted position, a slight amount of sagging will take place.

In order to support the outer end of the extensible frame, any suitable means may be provided, as for example, a foldable leg. It may be desirable to provide additional reinforcing means for the arms 6 and 7, although it is not considered necessary to explain in detail these changes which would be obvious to one skilled in this art.

While I have shown and described my invention in connection with a davenport, it is to be understood that the above description is given merely by way of illustration and not of limitation, because the features herein shown and described, may be admirably adapted for other uses.

Having thus described my invention, what I claim as new and desire to secure by Letters Patent is:

1. An article of furniture comprising a stationary main frame, guides at opposite ends of said frame, arms having one end portion slideable in said guides, interconnected spring elements having their end portions slideable on said arms, and means for forcing one of said arms outwardly to stretch said elements to supporting position.

2. An article of furniture comprising a

stationary main frame, guides on opposite sides of said frame, one of said guides being inclined outwardly from the back to the front of the frame, arms having their inner ends slideable in said guides, spring elements having their end portions slideable on said arms, means for interconnecting said spring elements to each other and to said panel, and means for drawing said spring elements taut thereby to form a cushioned supporting surface.

3. An article of furniture comprising a stationary main frame, guides on opposite sides of said frame, one of said guides being inclined, arms having their end portions slideable in said guides and extensible outwardly from said frame, a front panel for said frame, means for securing one of said arms to said panel, and means for forcing the other arm laterally, spring elements having their ends slideable on said arms, and means interconnecting said spring elements and panel.

In testimony whereof I have hereunto signed my name to this specification.

JAMES J. SULLIVAN.
